(57) **CLAIM**

The ornamental design for a novelty hat, as shown and
described.

DESCRIPTION

FIG. 1 is a front elevational view of the hat as intended to
be worn, with strands of the hat bending in multiple direc-
tions.

FIG. 2 is a front view of the hat as manufactured.

FIG. 3 is a rear view of the hat as manufactured; and,
FIG. 4 is a side view of the hat as manufactured.

The broken lines showing environment in the drawings are
for illustrative purposes only and form no part of the claimed
design.
